TOY GUN

Joseph Goodman, New York, N. Y.

Application May 10, 1949, Serial No. 2,547

Term of patent 3½ years

(Cl. D34—15)

To all whom it may concern:

Be it known that I, Joseph Goodman, a citizen of the United States and a resident of 20—81 Wallace Avenue, county of Bronx, city and State of New York, have invented a new, original, and ornamental Design for Toy Gun, of which the following is a specification, reference being had to the accompanying drawing, forming a part thereof.

On the drawing:

Figure 1 is a top plan view of the toy gun, showing my new design;

Figure 2 is a side elevational view thereof;

Figure 3 is a rear elevational view thereof;

Figure 4 is a front elevational view thereof; and

Figure 5 is a bottom plan view thereof.

The side of the toy gun not shown has substantially the same appearance as the side shown in Figure 2.

I claim:

The ornamental design for a toy gun, as shown and described.

JOSEPH GOODMAN.
